UNITED STATES PATENT OFFICE.

BENITO MONTOYA, OF LOS ANGELES, CALIFORNIA.

LUBRICATOR.

Application filed September 18, 1925. Serial No. 57,151.

My invention is in a lubricator adapted for locomotives and comprises forced feed oil storage containers adapted to force the oil to lubricating appliances connected to the locomotive.

An object of my invention is to provide reservoirs for oil having steam operated pistons for forcing the oil from the reservoirs to lubricating appliances such as the 10 flange oiler device and cylinder lubricating devices which are standard on locomotives.

In my invention I utilize a container having a pair of cylinders with pistons therein, each of the cylinders having a different type 15 of lubricating oil and having pistons mounted in the cylinders with a steam connection whereby steam may be forced into the cylinders and force the oil outwardly; such oil being led by pipes to lubricating 20 devices which are so designed that they can only hold a limited amount of oil.

Another feature of my invention is in passing the steam through the container to maintain the oil at proper temperature and 25 fluidity with manually controlled valves positioned in a base plate of the container to govern the flow of steam.

Various other features of my invention pertain to the details of construction of the 30 container and oil cylinders.

My invention will be more readily understood from the following description and drawings, in which;

Figure 1 is an elevation of my oil reservoir container, indicating a system of steam piping leading thereto and a system of oil pipes leading therefrom to locomotive oiling appliances.

Fig. 2 is a side view of Fig. 1 in the direction of the arrow 2.

Fig. 3 is a top view of my reservoir container taken in the direction of the arrow 3 of Fig. 1.

Fig. 4 is a vertical longitudinal section 45 of my reservoir container taken on the line 4-4 of Fig. 3 in the direction of the arrows, showing the oil cylinders.

Fig. 5 is a horizontal cross section of Fig. 4 on the line 5-5 in the direction of the 50 arrows.

Fig. 6 is a horizontal section of Fig. 4 on the line 6-6 in the direction of the arrows, indicating the oil cylinders.

Referring particularly to Figs. 1 and 2, 55 my oil reservoir container is indicated generally by the numeral 1; a standard flange

oiling device is designated by the numeral 2; a cylinder valve lubricator by the numeral 3; a steam supply dome is designated by the numeral 4, connected to the boiler 60 5. As the flange oiler 2 and the valve cylinder lubricator 3, together with the steam dome do not form a definite feature of my invention, they will not be more fully described. 65

My oil reservoir container 1 is preferably formed of a relatively large cast body 10 having a pair of oil cylinders 11 and 12 formed at the lower end; these cylinders have an open base closed by a cover plate 70 13 secured by bolts 14 to the metal structure of the cylinders. An oil reservoir 15 is constructed in the upper part of the container preferably by coring in the casting operation and is closed by a filler plug 16 75 and has an outlet tap 17 through which oil may be drawn to fill the oil cans utilized by the engine crew.

The steam operating features of my oil reservoir comprises a piston 20 in each of 80 the cylinders 11 and 12 each having a piston rod 21 extending upwardly into spring boxes 22, the latter being formed by coring the casting and the piston rods having heads 23. Compression springs 24 are housed in 85 the spring boxes and are under compression between the piston rod heads 23 and the screw threaded plugs 25 closing the upper ends of the spring boxes.

Steam is fed under the pressure to the oil 90 cylinders beneath the pistons by means of inlet oil pipes 30 having valves 31, ducts 32 extending downwardly through the casting of the container and horizontal connections 33 leading into the steam chamber 34. The 95 steam has a passage 35 through the casting at the rim of the cylinders through an aperture 36 in the cover plate 13 and enters a T 37. This T leads to branch pipes 38, having globe valves 39, the latter having 100 nipples 40 leading through the cover plate 13 to the lower side of each of the pistons 20. Drain cocks 41 are likewise provided in the cover plate 13 to allow drainage of the water condensed from the steam. A 105 steam blow off outlet is provided by a horizontal duct 42 from the steam chamber 34 to the vertical duct 43 which latter leads to a blow off pipe 44 controlled by the valve 45.

The oil is charged into the oil cylinders 110 through similar plugs 50 mounted in the reservoir casing above the cylinders and is

fed out of each of the cylinders through oil pipes 51 and 52 each having valves 53. The oil pipe 51 is shown as leading to the flange oiler 2 and the pipe 52 to the cylinder 5 valve lubricator 3.

A pair of sight holes 54 are provided with glass covers so that a person may ascertain if the oil cylinders contain oil.

The manner of operation of my lubricator container is substantially as follows: It will be understood that before beginning a run on a locomotive that the reservoir 15 will be filled with oil through the plug 16 and that the oil cylinders 11 and 12 will be filled through the plugs 50, with the pistons 20 in their bottom position resting on the cover plate 12. As the oil in the flange oiler 2 and the valve oiler 3 are used up the valve 39 may be opened to feed steam 20 from the steam chamber 34 to the base of either of the cylinders 11 and 12, it being understood that the steam valve 31 will normally be opened to allow steam to enter the steam chamber and to maintain the oil at proper temperature.

My invention may be considerably changed in general construction and in detail to suit it for supplying oil to different types of lubricating appliances, such changes being within the scope of my invention as expressed in the claims.

Having described my invention, what I claim is:

1. A lubricator reservoir comprising an integral body structure having a plurality of oil cylinders formed therein, a cover plate for the base of the cylinders, pistons in the cylinders, means to fill the cylinders with oil, a steam chamber in the body structure adjacent the cylinders, means for conducting steam through the body structure to and from the steam chamber, and means for conducting steam from the steam chamber through the cover plate to the base of the pistons.

2. A lubricator reservoir as claimed in claim 1, having in addition a plurality of bores in the body structure above the cylinders forming spring boxes, piston rods con-

nected to the pistons slideable in said boxes 50 and compression springs in said boxes.

3. A lubricator reservoir comprising a container having a body structure with a cylinder formed in the lower portion thereof and a tubular coring in the upper portion forming a spring box and having an opening connecting the cylinder and the spring box, a cover plate attached to the lower end of the cylinder, a plug at the upper end of the spring box coring, a piston 60 slideable in the cylinder, having a piston rod extending through the opening in the cored section, the piston rod having a head thereon, a spring in the cored section bearing against the piston rod head and said 65 plug, means to introduce oil into the cylinder, a pipe leading through the cover plate to flow steam into the cylinder below the piston, a pipe leading from the upper portion of the cylinder to a lubricating device, 70 a steam chamber in the body structure adjacent the cylinder and steam ducts through the body structure leading to the steam chamber and a steam pipe connected to the steam chamber through the cover plate and 75 to the pipe leading into the cylinder.

4. A lubricator reservoir comprising a container formed of a body structure having a reservoir in its upper portion and a pair of oil cylinders in its lower portion, a 80 cover plate closing the cylinders, a piston in each of the cylinders, means to introduce oil into the reservoir and the cylinders, pipes conducting steam through the 85 cover plate into the cylinders below the pistons, pipes to discharge oil from the cylinders to lubricating devices, an outlet tap for oil from the reservoir, a steam chamber in the lower portion of the body structure between the cylinders, and ducts conveying 90 steam through the body structure to the steam chamber and from the steam chamber to the pipes leading through the cover plate.

In testimony whereof I have signed my 95 name to this specification.

BENITO MONTOYA.
